UNITED STATES PATENT OFFICE.

HUGH LEITCH, OF REGINA, SASKATCHEWAN, CANADA.

ANTISEPTIC FLUSH-TANK.

1,220,243.

Specification of Letters Patent.

Patented Mar. 27, 1917.

Application filed April 27, 1916. Serial No. 94,063.

To all whom it may concern:

Be it known that I, HUGH LEITCH, a subject of the King of Great Britain, and resident of Regina, in the Province of 5 Saskatchewan, Dominion of Canada, have invented certain new and useful Improvements in Antiseptic Flush-Tanks, of which the following is the specification.

This invention relates to improvements in 10 antiseptic flush tanks particularly adapted for use in dentistry, and the objects of the invention are to facilitate in keeping to hand an adequate supply of hot antiseptic liquid wherewith teeth may be flushed; to 15 simplify the construction of the tank and generally adapt it to better perform the functions required of it, and it consists essentially of the improved construction particularly described and set forth in the 20 following specification and accompanying drawings forming part of the same.

In the drawing,

The figure is a vertical section of the 25 improved flush tank and showing the syringe partly in section and partly in elevation.

In the drawing, A represents the improved flush tank comprising the inner container 10 inclosed in a vacuum jacket 11 and separated therefrom by distance pieces 12, the said container being provided with an inlet conduit 13 which extends through the vacuum jacket and is provided on the upper end with a cap 14 threaded 35 or otherwise fastened thereon.

Operatively mounted in the container 10 is a pump 15, the upper end of which projects beyond the vacuum jacket 11, while the lower end extends midway of the height 40 of the container. The pump comprises a barrel 16 with which the plunger 17 slidably engages. This plunger is operatively connected to the lower end of the plunger rod 18, the upper end of which is provided 45 with a hand grip 19 thereby facilitating in manually operating the plunger.

The lower end of the pump is provided with a discharge valve 20 normally engaging with the discharge orifice 21 of the barrel 16, the said valve being held in a normal position by means of the spiral spring 22 operatively mounted on the pins 23 formed integral with the barrel 16 of the pump.

The liquid is discharged from the container 10 through the pipe 24, the upper

end of which extends through the casing 10 and the vacuum jacket 11 and is operatively connected to one end of the flexible tube 25 which is provided with a vacuum jacket 26 extending therearound, the other 60 end of the tube being connected to the syringe 27 which is provided with a vacuum jacket 28 and carries intermediate of its length a valve 29 adapted to control the passage of liquid through the syringe. 65

The lower or free end of the syringe may be provided with an interchangeable nozzle 30 of any usual description well known in the profession of dentistry. The upper end of the container 10 and vacuum jacket 11 70 are inclosed by a suitable cap 31.

The assembly of the tank will be readily understood from the foregoing description.

When the tank is in use the cap 31 is removed and a supply of heated liquid, 75 such as water or the like, is poured into the container 10 through the conduit 13 whereupon the cap 14 is located in position, and when it is found necessary to use the liquid in the container 10 it is only necessary to manually actuate the plunger rod 18 whereby air is delivered into the container 10 and the liquid contained therein is forced through the discharge pipe 24 and the flexible pipe 25 to the syringe 28 whereupon when the valve 29 is opened the liquid sprays through the nozzle 30 which may be inserted in the mouth to flush the teeth. 85

From this description it will be seen that I have invented a flush tank which can be 90 advantageously used by dentists and by means of which a considerable volume of antiseptic liquid may be always kept at hand at the desired temperature required for flushing the teeth or mouth of the 95 patient.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense. 100 105

What I claim as my invention is:

A device of the class described comprising a main tank, permanent end closures therefor forming an air tight inclosure, a liquid carrying container in said inclosure, 110

means for spacing said container from the walls of the closure, said inclosure being exhausted of air, an air pump and a filling neck carried by said container and projecting through one end closure, a cap on said neck, a pipe extending from the bottom of the container through the walls thereof and the tank and terminating in a valved nozzle, and a cover for the upper end of the tank.

10

In witness whereof I have hereunto set my hand in the presence of two witnesses.

HUGH LEITCH.
